(57) **CLAIM**

The ornamental design for a portable wireless communication device, as shown and described.

DESCRIPTION

FIG. 1 is a right, front and top perspective view of a portable wireless communication device;

FIG. 2 is a left, front and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines shown in the drawings illustrate portions of the portable wireless communication device that form no part of the claimed design.
